United States Patent Office

Des. 180,542
Patented July 2, 1957

180,542

SEWING CHAIR

Sophia Barrow, Port Arthur, Tex.

Application July 19, 1956, Serial No. 42,303

Term of patent 7 years

(Cl. D15—1)

Figure 1 is a perspective view of the chair showing drawers in open position extending from opposite ends of the chair seat, and

The rear of the seat portion is similar to the front and the back rest members are integral with the rear chair legs.

I claim:

The ornamental design for a sewing chair, as shown and described.
